[57] CLAIM

The ornamental design for a return top rattle toy, substantially as shown and described.

DESCRIPTION

FIG. 1 is a perspective view of a return top rattle showing our new design;

FIG. 2 is a top plan view thereof;

FIG. 3 is a front elevational view thereof, the side opposite being substantially a mirror image;

FIG. 4 is a right side elevational view thereof, the side opposite being substantially a mirror image; and,

FIG. 5 is a cross-sectional view thereof taken from line 5—5 in FIG. 2.
